Des. 188,420
Patented July 19, 1960

188,420

WELDING APPARATUS HOUSING

Thayer R. Brunson and Harold G. Davis, Denver, Colo.,
assignors to Rocky Mountain Metal Products Co., Den-
ver, Colo., a corporation of Colorado

Filed Aug. 5, 1957, Ser. No. 47,237

Term of patent 14 years

(Cl. D26—1)

Fig. 1

Fig. 2

Fig. 3

Figure 1 is a perspective view of a welding apparatus housing, showing our new design;

Figure 2 is a side elevational view the opposite side being a substantial mirror image thereof; and

Figure 3 is a front elevational view thereof.

The rear thereof, not shown, is conventional.

We claim:

The ornamental design for a welding apparatus housing, as shown and described.
